Henry R. Jackson,

BY Drakes, Co., ATTYS.

UNITED STATES PATENT OFFICE.

HENRY R. JACKSON, OF NEWARK, NEW JERSEY.

SASH-FASTENER.

SPECIFICATION forming part of Letters Patent No. 349,431, dated September 21, 1886.

Application filed April 16, 1886. Serial No. 199,051. (No model.)

To all whom it may concern:

Be it known that I, HENRY R. JACKSON, a citizen of the United States, residing at Newark, in the county of Essex and State of New Jersey, have invented certain new and useful Improvements in Window Catches and Sashes; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to improvements in car and window sashes, and provides a combined catch and lifting device by which the sash is locked, and which enables the person opening the same to use but one hand in unhooking and lifting the sash, the object of the invention being to secure a more positive and effective operation of parts, to secure increased strength and durability in the catch, and to reduce the number of projecting parts at the lower edge of the sash, which mar the appearance of the same and upon which the garments of the passenger or person operating said sash may catch and be torn or disarranged.

The invention consists in the combination of parts, substantially as indicated in the drawings, and described and claimed hereinafter.

In said drawings, in which similar letters of reference indicate corresponding parts in each of the views, Figure 1 is an elevation, partly in section, of a car-sash illustrating the relation of the invention thereto. Fig. 2 is a front elevation of the catch and lifting device detached from the sash. Fig. 3 is a rear elevation of said catch, &c., and a portion of the sill. Fig. 4 is a top view of the casing and thumb or finger piece; and Fig. 5 is a section taken through line α , Fig. 3.

In the drawings, A indicates the window-frame, B the sash, and C the groove in the window-jamb in which the sash slides. Within the groove in the jamb is arranged a binding-strip, c , which is held against the stiles of the sash by springs c' , either one of said binding-strips on one side of the sash being used, or two, one on opposite sides of the sash. The said strip c acts as a friction-piece, and pressing against the sash holds it in any position to

which the said sash is elevated, the strength of the springs being accommodated to the weight of the sash, and of such power as to hold the sash at any point, but still allow the sash to be readily raised and lowered. At the bottom of the window-sash is arranged the combined catch and lifter, which consists of a casing, d , within which is pivoted a spring-actuated hook, e , provided with a finger-piece, e' , extending through a slot, f , in the side of the casing out beneath the lifting-plate g , the said finger-piece and hook working in a plane parallel with the face of the sash, or with the outer face of the casing d or part h , so as not to project materially from said casing, but yet allow of sufficient leverage. The said finger-piece lies in close contiguity to the part d of the casing and beneath the lifting-plate g at the base thereof, and is thus to a great extent hidden from view by the latter, so that the appearance of the sash is not marred thereby. The hooked extremity of the lever is provided with the bevel or incline e'' , Fig. 3, so that when the sash is lowered the hook will be automatically repressed by the co-operating sill-catch prior to springing automatically into latching relation thereto. The said hooked extremity lies within and is covered by the casing, so that it will not be objectionable, as above described, in catching the garments or hat of the passenger in looking out of the window, as will be understood. The said plate g is formed integrally with the casing, or with a part, h , thereof, in which the screw-holes i are made, said lifting-plate being disposed at or near the upper edge of said part h , and projecting out sufficiently to provide a secure purchase for the fingers. A hook, j , is secured to the sill k and projects up into the casing when in engagement with the pivoted hook e , as indicated in Fig. 3, in which view the spring l is shown. When the sash is to be raised, the finger is inserted under the plate g and lifts the finger-piece of the catch until it clears the hook j , the said finger-piece striking the under side of the plate g , so that the latter takes the force of the finger exerted in lifting the sash, and provides a rigid or immovable bearing for the finger, so that the operator has full control of the catch and sash.

In certain devices heretofore in use, where

a lifting-plate and catch finger-piece have been arranged one over the other, the movable finger-piece has extended in a direction parallel with the rigid lifting-projection, and in appearance closely resembled it, and thus was liable to be grasped in lifting the sash—an objection that is obviated by the construction of the improvement above described. The sash can then be raised to any desired height. In this manner but one movement of the hand is necessary to release the catch and seize the lifting-plate. As indicated in the drawings, it will be seen that the pull or power comes directly upon the screws which pass through the portion *h* beneath the lifting-plate, as shown in Figs. 1 and 2.

If necessary to secure additional stiffness, a flange may be formed on the casing, as dotted in Fig. 2, to receive a screw.

Having thus described the invention, what I claim is—

In a combined catch and lifter, the combination of a casing having the perforated portion *h*, a spring-actuated catch arranged in said casing and working pivotally in a plane parallel with said perforated portion, and a rigid lifting-plate integral with the casing and overlying the finger-piece of the catch, substantially as set forth.

In testimony that I claim the foregoing I have hereunto set my hand this 17th day of March, 1886.

HENRY R. JACKSON.
